P. H. KENNEY

PISTON REMOVING DEVICE

Filed Nov. 27, 1925

UNITED STATES PATENT OFFICE.

PATRICK H. KENNEY, OF CUMBERLAND, MARYLAND.

PISTON-REMOVING DEVICE.

Application filed November 27, 1925. Serial No. 71,692.

This invention relates to a device for removing a piston from the cross-head of a locomotive or other type of engine.

The principal object of this invention is 5 the provision of an improved means for removing the piston from the cross-head expeditiously and without injury to the said cross-head.

Another important object of this invention 10 is the provision of a device for removing the piston from the cross-head adapted to be operatively positioned in the cross-head and including a plunger and means for forcing the same in piston removing direction.

With these and other objects in view, which will become apparent as the description proceeds, the invention resides in the construction, combination and arrangement 15 of parts, hereinafter more fully described and claimed, and illustrated in the accompanying drawings, in which like characters of reference indicate like parts throughout the several figures, of which:

20 Fig. 1 is a perspective view of my piston removing device showing the wedge and brace members operatively positioned;

Fig. 2 is a longitudinal section through the cross-head and block showing the wrist 25 pin, plunger, and wedge member in elevation; and

Fig. 3 is an end view of the cross-head with the device operatively positioned therein, showing the hammer and its support in 30 side elevation.

The expeditious removal of a piston from the cross-head of a locomotive has been a problem that has occupied the attention of those skilled in the art since the advent of 40 the present form of engine, owing to the fact that the piston becoming "frozen" renders removal very difficult without injury to the cross-head, since the location of the cross-head with respect to the engine precludes the utilization of means which 45 ordinarily could be employed.

In view of the above, the devices with which I am familiar have proven unsatisfactory, and it was to overcome the deficiencies 50 of such devices, and to provide one constructed to prevent injury to the cross-head, yet embodying means for transmitting a powerful force to the piston in removing direction, that I designed the device forming 55 the subject matter of this invention.

In the illustrated embodiment character-

izing this invention there is shown a block 1 of substantially rectangular shape adapted to fit within the cross-head 2; and it is to be understood that the configuration of the 60 said block may conform to that of the particular cross-head in connection with which it is employed.

The block 1 is formed with a central longitudinal bore 3 adapted to receive the 65 plunger 4, and with a transverse bore 5 spaced from the forward end of the block and through which is insertable the pin 6 having a transverse bore 7 adapted to register with the bore 3 for a purpose which will 70 hereinafter more fully appear. The pin 6 conforms substantially in size and configuration to the wrist pin (not shown) normally seating in the bearing openings 11 of the cross-head 2.

The block 1 is also formed with a transverse aperture 8 spaced from its rear end intersecting the central bore 3, and having its rear vertical wall tapering forwardly against which is adapted to slide the inclined wedge face 9 of the wedge member 10 when the said member is operatively positioned in said aperture, the plane face 12 adapted for slidable wedging engagement with the rear end 13 of the plunger 4 when 85 driving force is transmitted to the wedge member 10 by hammer 14 swung in the same longitudinal plane as the said wedge member by cable or other suitable means 15 secured to the upper end of the angularly 90 positioned supporting member of standard 16 the lower end of said supporting standard adapted to seat in aperture 17 in the block 1 vertically spaced with respect to aperture 8.

It will be noted that when the block 1 is 95 operatively positioned in the crosshead 2 it is anchored against longitudinal movement by the pin 6 extending through the registering openings 11 and 5, and in order to insure against lateral movement the vertically 100 spaced parallelly extending brace members 18 are provided with their inner ends seating in suitable bores in the said block 1 as at 19 and their free extremities adapted to seat against the engine.

As above stated, owing to the piston 20 being so firmly secured in the crosshead 2, it has been found that such gradual pressure as could be brought to bear against the inner end of the piston, in view of the awkward 110 position in which it is necessary to work, would seldom dislodge it without in some

manner breaking or injuring the cross-head and without a great expenditure of time and labor, and in order to overcome such difficulties I designed the above described device 5 from which the operation would seem to be clear, however, I desire to note certain features in connection with its operation of special importance, as follows.

When the block 1 has been operatively positioned 10 in the cross-head, the pin 6 extending therethrough, the free or outer end of the plunger 4 contacting with the inner end of the piston 20, the wedge 10 inserted partially in the aperture 8 and contacting the 15 rear end of said plunger, the hammer 14 weighing approximately 250 pounds or designed to strike an equally heavy blow is brought into sudden contact with the outer end of the wedge 10, thereby transmitting a 20 sharp, powerful force suddenly to the rear end of the piston through the instrumentality of the plunger 4, disengaging the piston from the cross-head.

It is apparent that a heavy sudden jarring 25 movement will dislodge a piston that otherwise would withstand a powerful force gradually transmitted.

Although in practice I have found that the 30 form of my invention illustrated in the accompanying drawings and referred to in the above description as the preferred embodiment, is the most efficient and practical, yet realizing the conditions concurrent with the adoption of my device will necessarily vary, 35 I desire to emphasize that various minor changes in details of construction, proportion and arrangement of parts, may be resorted to within the scope of the appended 40 claims without departing from or sacrificing any of the principles of this invention.

Having thus described my invention, what 45 I desire protected by Letters Patent is as set forth in the following claims:

1. A piston removing device adapted to be used with a cross-head having a piston se-

cured therein and having wrist pin openings, said removing device including a block member corresponding to the interior dimensions of the cross-head and adapted to seat therein, an anchoring pin adapted to extend transversely through said block and said wrist pin openings to lock the block against longitudinal movement, a plunger movable in said block in longitudinal alignment with said piston, a transverse aperture through 55 said block in spaced parallelism with said anchoring pin, a wedge member movable in the aperture at right angles to the plunger for coaction therewith, a hammer means carried by the block adapted to contact with said wedge to impart thereto a sudden heavy blow for transmission to said piston through the instrumentality of said plunger to effect removal of the piston from the cross-head. 65

2. A piston removing device adapted to be used with a cross-head having a piston secured therein and having wrist pin openings, said removing device including a block member corresponding to the interior dimensions 70 of the cross-head and adapted to seat therein, said block having a transverse bore adapted to register with the wrist pin openings, means insertable through said openings and bore to lock the block against longitudinal 75 movement, a plunger longitudinally movable in said block, a wedge member transversely movable through the block in spaced parallelism with said transverse bore and adapted to coact with said plunger, hammer means 80 carried by the block and operable to contact said wedge to impart thereto a heavy blow for transmission to said piston through the instrumentality of the plunger to effect removal of the piston from the cross-head, and 85 brace means carried by the block and adapted to prevent lateral movement thereof when the hammer contacts said wedge.

PATRICK H. KENNEY.
